COMPACT SLITTING MECHANISM

Elvin A. Mastriani, Roseland, and Robert E. Mastriani,
Long Valley, N.J., assignors to Arrow Converting
Equipment, Inc., Fairfield, N.J.

Filed June 3, 1975, Ser. No. 583,151

Term of patent 14 years

Int. Cl. D15—99

U.S. Cl. D15—127

FIG. 1

FIG. 2

FIG. 1 is a side elevational view of a compact slitting mechanism showing our new design, the side opposite being a mirror image thereof, and

FIG. 2 is a top plan view thereof taken at line 2—2 of FIG. 1.

We claim:

The ornamental design for compact slitting mechanism, substantially as shown and described.
